UNITED STATES PATENT OFFICE.

DAVID PATON, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,895, dated June 4, 1872.

To all whom it may concern:

Specification describing a new and original Design for a Carpet, invented by DAVID PATON, of Halifax, in the county of York, England.

The accompanying photograph fully illustrates my invention.

This invention relates to a new floral design, for carpets, in which series of branches, studded with flowers and leaves, are fantastically displayed, in the manner shown.

I claim as my invention—

The design for a carpet, as shown.

DAVID PATON.
